United States Patent Office.

JOHN D. LYNDE, OF PHILADELPHIA, PENNSYLVANIA.

Letters Patent No. 74,889, dated February 11, 1868.

IMPROVEMENT IN WATER-INDICATORS FOR BOILERS.

The Schedule referred to in these Letters Patent and making part of the same.

Be it known that I, JOHN D. LYNDE, of Philadelphia, in the county of Philadelphia, and State of Pennsylvania, have invented a new and useful Machine for Preventing Low Water in Steam-Boilers; and I do hereby declare that the following is a full, clear, and exact description of the construction and operation of the same, reference being had to the annexed drawings, making a part of this specification, in which—

Figure 1 is a perspective view.

Figure 2, a longitudinal elevation.

A is a cast-iron case, connected to the boiler by the pipe C, which may be of a convenient length to suit the position, and supplied with a steam-cock, to close the communication, when desired. B is a metallic tubal float, made of a size that will enter the aperture in A, and hung at one end on the pin D by the lever G. E is a brass mouth-piece and valve-case. F is a valve-stem and valve. H is a conical spiral spring, which holds valve F on its seat. I, valve-seat and stopper to E. K is a brass cap, which supports the whistle L, the detached valve-stem M, and is held firmly upright by a set-screw.

The operation is as follows: The pipe C is connected with the boiler at the lowest line to which it is desirable the water should reach, or at which it would be necessary to add more water for regular working purposes. When the water is above the pipe C in the boiler, the pressure of steam will keep A filled nearly with water, and the float B will be raised, the dotted line being the surface of the water. The indicator may now be used as a gauge-cock, (and it would very properly be put in the place of the usual middle gauge) by pressing on the detached valve-stem at O. F is pushed from its seat, and water runs from the pipe N. When the water in the boiler begins to fall below the top of the aperture in pipe C, the water will drop out of A, the float B falls, tipping the valve-stem F by the lever G, and the valve will be opened sufficiently to allow steam to escape and sound the whistle. Start the pump or injector, and as soon as the water rises, the indicator, being automatic, will cease to whistle.

The object of this invention is to obviate the difficulties experienced in similar articles from sediment, deposits of lime, sticking of valves, &c., which prevent the desired operation. The valve being constantly in use as a gauge, cannot get fast. It is especially intended to prevent low water, by indicating when water is needed, as described above. It is found to much more correctly indicate the water than the common gauge-cock, as in many cases, especially with locomotive-boilers, the gauge, if opened suddenly, will deceive the engineer by showing water from the foam, and ebullition, if the water is a little low and the fire extremely hot; while in this indicator the water is always still, and not affected by the action in the boiler, and when the real surface of the water reaches the connecting-pipe C, it will at once be known, as the foam and attenuated water are not sufficient to keep the indicator filled; consequently a call for more water would be heard.

What I claim as my invention, and desire to secure by Letters Patent, is—

The arrangement of the lever G, valve-stem F, spring H, valve M, pipe N, with reference to the float B, whistle L, and case A, whereby to sound an alarm when the water is too low in the boiler, and to ascertain the condition of the water at other times, substantially as set forth.

JOHN D. LYNDE.
